ABSTRACT OF THE DISCLOSURE

At least two electromagnetic selectors are placed at each knitting station of a circular knitting machine for respectively selecting and operating resilient control elements which are arranged in at least two circumferential rows on the needle cylinder of the circular knitting machine and control the selection and operation of needle influencing jacks. The electromagnetic selectors and the rows of control elements are spaced in axial direction of the needle cylinder so that alternating control elements are staggered whereby more circumferential space is available for each control element.

CROSS-REFERENCE TO RELATED APPLICATIONS

The copending application Ser. No. 436,614, now U.S. Patent 3,365,916 filed by Ribler et al. on Mar. 2, 1965, and entitled "Selector Magnet Arrangement" and the copending application Ser. No. 532,304 filed by Schmidt et al. on Mar. 7, 1966, and entitled "Selector Apparatus" disclose arrangements which can be improved by the present invention.

BACKGROUND OF THE INVENTION

The above-mentioned copending applications disclose circular knitting machines whose cylinder needles and/or dial needles are operated by needle influencing jacks which are selectively controlled by resilient control elements selected for actuation by electromagnetic selector means.

In my U.S. Patent No. 3,292,393, the needle influencing jacks are spring biased and locked by the control elements until the same are moved by an electromagnetic selector to a position releasing the respective jacks.

In the copending application Ser. No. 532,304, the jacks are pivotally mounted and are angularly displaced by resilient control elements selectively operated by the electromagnetic selector.

The construction disclosed in the application Ser. No. 436,614, now U.S. Patent 3,365,916 is similar to the construction disclosed in my U.S. Patent 3,292,393.

In circular knitting machines of this type, the control elements and correlated jacks and needles are arranged in a circumferentially extending row. For constructive reasons, the control elements must be closely spaced from each other and consequently have to be constructed as thin resilient wires which do not always accomplish the desired control function with the accuracy required for the knitting of a perfect pattern.

SUMMARY OF THE INVENTION

It is one object of the invention to overcome this disadvantage of prior constructions, and to provide a circular knitting machine with a selector arrangement affording more circumferential space for each control element.

Another object of the invention is to provide more circumferential space for each control element so that the use of thicker and stronger control elements is possible.

2

Another object of the invention is to stagger adjacent control elements.

With these objects in view, one embodiment of the invention is applied to a circular knitting machine and comprises carrier means, for example the needle cylinder or dial of the knitting machine; a set of needle influencing elements mounted on the carrier means; a number of selector means located at a selecting station spaced from each other the same distance as the selector means and and selectively actuated in accordance with a program representing a knitting pattern; and the same number of circumferential rows of control elements spaced from each other the same distance as the selector means and respectively passing the selector means during rotation of the carrier means.

The control elements are respectively aligned with the needle influencing elements and are selectively actuated by the selector means to cause movement of the respective correlated needle influencing elements.

20 The displaced needle influencing elements operate the needles.

The control elements are disposed in the circumferential rows so that adjacent control elements are staggered in a direction transverse to the circumferential direction of the carrier means. For example, control elements mounted on a needle cylinder are arranged in a number of circumferential circular rows which are axially spaced, while the control elements which are mounted on the dial are arranged in a number of circular rows spaced in radial direction.

In a preferred embodiment of the invention two circular rows of control elements cooperate with one circular row of needle influencing elements and are respectively selected by two electromagnetic selector means which are program-controlled to be energized or deenergized during passage of control elements in accordance with a knitting pattern.

Particularly when the control elements are used for locking spring biased needle influencing elements, it is advantageous to provide an anchoring part on a resilient wire so that the thicker anchoring part is reliably attracted by the respective electromagnetic selector means or released by the same to reliably lock the respective needle influencing element. Due to the staggered disposition of the thick anchoring parts of the control elements, a greater circumferential space is available for the thick anchoring parts.

The use of two or more electromagnetic selector means instead of one, permits the use of smaller electromagnetic selector means and the magnetizable iron cores can be dimensioned in view of the greater available space. Due to the provision of several rows of control elements, the time period available for the selection by each electromagnetic selector means is lengthened, as compared with prior constructions, and is greater than the time of energization required for the selection. The dimensioning of all parts in circumferential direction is facilitated, which is particularly advantageous if the pitch of the control elements and needle influencing elements is small.

60 The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

BRIEF DESCRIPTION OF THE DRAWINGS

70 FIG. 1 comprises a plurality of fragmentary axial schematic sectional views FIG. 1A to FIG. 1E illustrating the

lector arrangement of the invention and being respectively taken in the regions A, B, C, D and E in FIG. 2; id

FIG. 2 is a fragmentary developed view taken in the direction of the arrow 2 in FIG. 1A.

FIG. 3 is a fragmentary schematic front view illustrating the selector arrangement according to a modified embodiment; and

FIG. 4 is a fragmentary axial sectional view taken on line IV-IV in FIG. 3.

DESCRIPTION OF THE PREFERRED EMBODIMENTS

Referring now particularly to FIGS. 1 and 2 which illustrate an arrangement according to the invention as applied to a circular knitting machine constructed in accordance with my U.S. Patent 3,292,393, the carrier means for needle influencing elements 1i forms part of a needle cylinder 3 which has axially extending peripheral spaced grooves 3a' in which cylinder needles 2 are mounted for axial movement. Grooves 3a' are formed between thin plates 3a set into the body of the needle cylinder. A cam cylinder 230 carries inner stationary cams 130 and 122 cooperating with butts 2' of needles 2 and located at a higher level, and cams 122 and 120 cooperating with butts 1i' of needle influencing elements or ticks 1i and located at a lower level.

Since needle influencing elements 1i and cylinder needles are located in the same axially extending grooves, elements 1i directly cooperate with the cylinder needles 2 to shift the cylinder needles in axial direction to a knit position. FIG. 1A shows one element 1i in an inoperative position urged by a biasing spring 111 to move toward the footend 2" of the correlated needle 2 whose butt 2' rests on cam 130, as also shown in FIG. 2. Each needle influencing element 1i cooperates with a control element 109. Two circumferential rows of control elements 109 are provided, the upper and lower rows respectively consisting of control elements 6o and 6u. Control elements 6u are shown in FIG. 1 substantially covered by control elements 6o. Circumferentially extending holding means 131 are schematically shown and include an upper holding means 131o and a lower holding means 131u for respectively holding the lower ends of the control elements 6o and 6u.

Each control element 109 has a hook portion 109b, the hook portions of the upper control elements 6o cooperating with slanted cutouts 1io of the respective aligned alternate needle influencing elements 1i, and the hook portions of the lower control elements 6u cooperating with lower cutouts 1iu of the respective correlated needle influencing elements.

Consequently, when a needle influencing element 1i is moved by its biasing spring 111 to an intermediate position shown in FIG. 1B, locking hook portion 109b of control elements 6o and 6u, respectively, can snap into the respective cutout 1io or 1iu. FIGS. 1A to 1E show positions of control elements 6o. Control elements 6u can assume corresponding positions while cooperating with the alternate series of elements 1i, having cutouts 1iu. In this locked position, the upper end of element 1i is spaced from the foot 2" of needle 2 whose butt 2' rides on cam 130.

Region B of FIG. 2, and FIG. 1B of FIG. 1 show a selecting station where two electromagnetic selector means 8o and 8u are provided for cooperation with the control elements 6o and 6u, respectively. Selector means 8o and 8u are only schematically shown in FIGS. 1 and 2, and are illustrated in greater detail in FIG. 4 to have windings 8w and pole shoes 8p. Electromagnetic selector means 8o and 8u are alternately used for making selections of control elements. When electromagnetic selector means 8o is energized in accordance with a program on a program tape, for example, it attracts the control element

6o passing by, and when electromagnetic selector means 8o is not energized, the locking portion 109b of the respective control element is permitted to enter cutout 1io of the respective needle influencing elements 1i and to lock the same in position shown in FIG. 1B, preventing upward movement of the needle influencing element by spring 111.

The same operation is performed by electromagnetic selector means 8u with control elements 6u in accordance with a program, and since control elements 6o and 6u alternately pass the selecting station, selector means 8o and 8u are alternately controlled in accordance with the program.

Several selecting stations may be provided around the needle cylinder.

In the position shown in FIG. 1C, spring 111 has moved a selected needle influencing element 1i, which is not locked, to a higher position in which its upper end abuts the foot 2" of a needle 2. In the next following position shown in FIG. 1D, cam 120 has moved element 1i to an even higher operative position while the upper end of the completely expanded spring 111 cannot follow element 1i, and since element 1i engages needle 2, the same is shifted to the knit position, while its butt 2' engages the lower face of stitch cam 121 which, as best seen in FIG. 2, lowers the needle until the same slides again on cam 130 in a lower cast off position.

At the same time, as shown in FIG. 1E and in region E of FIG. 2, a return cam portion 122a of cam 122 engages projection 1i' and moves element 1i downward to an inoperative position, and since cam 122a merges into cam 122 which extends around the circumference of the cam cylinder, all elements 1i will arrive in the region A of FIG. 2 in the position shown in FIG. 1a.

Cam 122 extends around the inner surface of the cam cylinder in a plane perpendicular to the axis of the needle cylinder 3, but in the region of the selecting station 115, cam 122 has an upwardly slanted cam portion 122', followed by a gap 132 between cam portion 122' and a rising cam 120 which has a rising portion between points C and D in FIG. 2. Cam 120 terminates after point D and is followed by the return cam 122a at point E.

Cam 130 extends also in a plane perpendicular to the axis of the needle cylinder to point C and has between points C and D a rising cam portion 130a which is designed to raise a needle whose butt 2' slides thereon to the tuck position. Needles passing over the end of cam portion 130a will be engaged by the lower face of stitch-cam 121 and guided to a position in which the butts thereof slidingly rest on the horizontal cam 130.

During rotation of the needle cylinder in the direction of the arrow in FIG. 2, the lower ends of needles returned by stitch cam 121 will push corresponding needle influencing elements 1i in the region between points D and E in FIG. 2 to a lower position so that the projections 1i' assume a lower position engaging the lower face of the slanted cam portion 122a so that all elements 1i are moved downwardly to the inoperative position shown in FIG. 1A. During such movement from the position shown in FIG. 1E to the position shown in FIG. 1A, the locking portion 109b of the respective upper control element 6o passes into the slanted recess 1io or 1iu of the respective element, but since the element moves downward, the slanted shoulder of recess 1io presses the locking portion 109b again out of the recess so that the locking portion rests on the outer edge of the respective element 1i in the position shown at A in FIG. 2, and in FIG. 1A.

As will become apparent from the following description, non-selected elements 1i will reach return cam portion 122a in the locking position shown in FIG. 1B in which locking portion 109b is located in the corresponding recess 1io or 1iu in a locking position. The downward slanting cam portion 122a will push elements 1i in this position downwardly to the position shown in FIG. 1A.

so that the slanted shoulders of the respective recess will also push the locking portion $109b$ out of the recess and to a position slidily engaging the edge of the respective element $1i$, as shown in FIG. 1A.

All needle influencing elements $1i$ arrive in the region of the selecting station at point B in the position shown in section A, and since the biasing springs 111 are tensioned in this lower inoperative position of elements $1i$, projections $1i'$ press against the lower cam face of cam 122 , and all elements $1i$ move upward to an intermediate position while the projections $1i$ slide along the short upwardly slanting cam portion $122'$.

Each electromagnetic selector located on selecting station 115 includes a permanent magnet $115a$ which acts on all control elements 109 to hold the same in the position shown in FIG. 1A or to bend the same away from element $1i$ to a position slidily abutting magnet $115a$. Thereafter, the control element moves with the needle cylinder 3 to a position located opposite electromagnetic selector means $115b$, and the selection is now made depending on whether selector means $115b$ of the upper selector $8o$ or the lower selector $8u$ is energized, or not energized from the program control device of the machine. Assuming that selector $115b$ of one of the two selector means is energized, it will hold control element 109 sliding thereon, releasing the respective element $1i$ to move upward in gap 132 . Non-selected control elements $6o$ or $6u$ snap into the respective recess $1io$ or $1iu$ and lock the needle influencing element.

The non-selected elements $1i$ remain locked as shown in FIG. 1B until projection $1i'$ is engaged by the downward slanting cam portion $122a$, and the respective element $1i$ is pushed downward so that locking portion $109b$ is pressed out of recess $1io$ or $1iu$ to the position shown in FIG. 1A. FIGS. 1C to 1E illustrate a selected element $1i$, so that for a non-selected element $1i$, the position shown in FIG. 1A follows the position shown in FIG. 1B.

In the region D of FIG. 2, the needle is in the knit position and is lowered by stitch cam 121 until butt $2'$ rests on cam portion 130 . Locking portion $109b$ momentarily snaps into cutout $1io$ or $1iu$ during the downward movement of the respective selected element $1i$, but is pushed out again by the slanted shoulders of the cutout to assume the position shown in FIG. 1A.

During the movement of a selected element $1i$ in gap 132 onto the pointed end of cam 120 , its control element 109 is held by permanent magnet $115c$ of the upper electromagnetic selector means $8o$ or lower electromagnetic selector means $8u$, whereupon control element 109 passes beyond the permanent magnets $115c$ and drops with its locking portion $109b$ onto the edge of the selected element $1i$, as shown in FIG. 10.

Referring now to FIGS. 3 and 4 which show modified details of the arrangement described with reference to FIGS. 1 and 2 on a larger scale, control elements 209 comprise a circular row of upper control elements $6o$ and a circular row of lower control elements $6u$ staggered in axial direction having hook portions $209b$. The control elements have projections $6o'$ and $6u'$ cooperating with short circumferential cams $20o$ and $20u$ rising in circumferential and radial directions which guide selected control elements in radial direction toward the selector magnets, and away from the cutouts $1io$ and $1iu$ in the needle influencing elements $1i$. Control elements which are not attracted snap back at the end of cam $20o$ and $20u$. The U-shaped holding means $7o$ and $7u$ are shown to be mounted in circular dovetail recesses $3o$ and $3u$ of the needle cylinder 3 secured by wedge members $7o'$ and $7u'$, respectively which spread the legs of holding means $7o$ and $7u$. The holding means $7o$ and $7u$ are made of flat plates, as best seen in FIG. 3 and carry wire parts 6 of the control elements. Each holding means $7o$ and $7u$ has two legs 50 , 51 connected by a curved yoke 52 , and having abutment portions $50a$, $51a$ and dovetail portions $50b$ and $51b$ matching the outline of the circular dovetail recesses $3o$ and $3u$ which surround the needle cylinder. A portion $50c$ of leg 50 has a tubular part in which a straight wire 6 is mounted. When control elements 209 ($6o$ or $6u$) are to be mounted on the needle cylinder, legs 50 and 51 are pressed together so that dovetail portions $50b$, $51b$ can be inserted into circumferentially extending dovetail recess $3o$ or $3u$. Upon release of the legs, the dovetails resiliently hold the respective control elements. To prevent accidental loosening, wedge portion 60 of a wedge member $7o'$ or $7u'$ is inserted between legs 50 , 51 and rigidly blocks inward movement of the same. A handle portion 61 is laterally staggered in relation to wedge portion 60 so that handle portion 61 is located laterally of yoke 52 , as best seen in FIG. 3. The sides of holding means $7o$ and $7u$ may abut divider plates $3a$ not shown in FIG. 3, set into the body of the needle cylinder and forming between each other the grooves for the needles and elements $1i$. Divider plates $3a$ have projections $13a$ for guiding control elements 209 . Anchoring parts $6b$ are secured to the wires 6 at the level of the respective electromagnetic selector means $8o$ or $8u$, as shown in FIGS. 3 and 4, and have hook portions co-operating with cutouts $1io$ and $1iu$, respectively, of the needle influencing elements. Due to the fact that adjacent control elements 209 are staggered in axial direction, sufficient space for the thicker anchoring portions $6b$ is available.

It will be seen that the staggered arrangement of the control elements results in a greater circumferential space for each control element, and for the electromagnetic selector means since one heavier selector magnet according to the prior art is replaced by two smaller axially spaced electromagnetic selector means $8o$ and $8u$ having a square cross section as shown in FIG. 3.

It will be understood that each of the elements described above, or two or more together, may also find a useful application in other types of selector arrangements differing from the types described above.

While the invention has been illustrated and described as embodied in a selector arrangement having two staggered circular rows of control elements respectively actuated by two selector magnets, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims:

1. Pattern controlling selector arrangement for a circular knitting machine, comprising, in combination, carrier means mounted for rotation about an axis; a set of needle influencing elements mounted on said carrier means for rotation therewith past at least one selecting station and for movement thereon between an inoperative position and an operative position for displacing a correlated needle; a plurality of electromagnetic selector means located at said selecting station spaced from each other a predetermined distance in a direction transverse to the circumferential direction of said carrier means, said selector means being successively and selectively actuated in accordance with a program representing a knitting pattern; and a plurality of circumferential rows of control elements, each control element including a resilient part and an anchoring part secured to said resilient part and being wider in circumferential direction than said resilient part, said anchoring parts forming a

plurality of circumferential rows respectively correlated with said selector means, said rows being spaced from each other said distance in said transverse direction, and respectively passing said selector means during rotation of said carrier means, said control elements being respectively aligned with said needle influencing elements and being selectively actuated by said selector means to cause movement of the respective correlated needle influencing element to said operative position, the number of all said control elements being equal to the number of said needle influencing elements and circumferentially adjacent anchoring parts of said control elements being staggered in said transverse direction and located in said circumferential rows, respectively, whereby more room is available for each anchoring part in said circumferential direction.

2. An arrangement as claimed in claim 1 wherein said resilient part of each control element is a resilient wire, and wherein said anchoring part is wider in circumferential direction than said wire part and has a hook portion cooperating with a correlated needle influencing means.

3. An arrangement as claimed in claim 1 wherein said carrier is a needle cylinder rotatable about an axis and having axially extending peripheral channels in which said needle influencing elements are mounted for axial movement; and wherein said transverse direction is the axial direction of said needle cylinder so that said electromagnetic selector means and said rows of anchoring parts are spaced in said axial direction.

4. An arrangement as claimed in claim 1, having two selector means, and two circular circumferential rows of anchoring parts so that alternate control elements are staggered in said transverse direction.

5. An arrangement as claimed in claim 1, wherein said carrier is a needle cylinder having axially extending channels in which said needle influencing elements are mounted for axial movement; and wherein said control elements resiliently tend to assume a normal position, and are actuated by said selector means to move to an actuated position causing movement of said needle influencing means to said operative position.

6. An arrangement as claimed in claim 5, comprising biasing means biasing said needle influencing means to move to said operative position; wherein said control means in said normal position lock said needle influencing means to prevent movement of the same to said operative position, and release said needle influencing means in said actuated position; and wherein said electromagnetic

selector means attract, when energized, said anchoring parts of said control elements of said rows, respectively, to move the same to said actuated position.

7. Pattern controlling selector arrangement for a circular knitting machine, comprising, in combination, carrier means mounted for rotation about an axis; a set of needle influencing elements mounted on said carrier means for rotation therewith past at least one selecting station and for movement thereon between an inoperative position and an operative position for displacing a correlated needle; a plurality of selector means located at said selecting station spaced from each other a predetermined distance in a direction transverse to the circumferential direction of said carrier means, said selector means being successively and selectively actuated in accordance with a program representing a knitting pattern; a plurality of circumferential rows of control elements respectively correlated with said selector means, said rows being spaced from each other said distance in said transverse direction, and respectively passing said selector means during rotation of said carrier means, said control elements being respectively aligned with said needle influencing elements and being selectively actuated by said selector means to cause movement of the respective correlated needle influencing element to said operative position, the number of all said control elements being equal to the number of said needle influencing elements, and circumferentially adjacent control elements being staggered in said transverse direction whereby more room is available for each control element in said circumferential direction; and a plurality of circumferential rows of holding means spaced in said transverse direction and respectively securing said rows of control elements to said carrier means.
